TION OF NEW YORK.

COUNTER MECHANISM.

1,141,623.

Specification of Letters Patent.

Patented June 1, 1915.

Original application filed June 21, 1911, Serial No. 634,395. Divided and this application filed January 8, 1914. Serial No. 811,087.

To all whom it may concern:

Be it known that I, CHARLES J. FANCHER, a citizen of the United States of America, residing at Thompsonville, in the county of 5 Hartford and State of Connecticut, have invented new and useful Counter Mechanism, of which the following is a specification.

My invention relates to improvements in mechanism for automatically counting units, 10 such as postage stamps, as they are actuated through a machine, such as a stamp affixer, in the process of separating and affixing them to objects or articles, such as envelopes, and consists of certain peculiar parts 15 and combinations of parts, all as hereinafter set forth.

This application is a divisional part of my application for United States Letters Patent, filed June 21, 1911, Serial No. 634,395.

20 Heretofore mechanism has been provided to record the stroke of a machine which delivers units, as, for example, in certain stamp affixers, where the strokes of the plungers or other operating parts are recorded, regardless of the result produced by such strokes, 25 that is to say, a record is made of each complete operative pulsation, as well when no stamp is affixed, or even present in the machine, as when the actual affixing of a stamp 30 is brought about. This is a serious defect in such a machine, because of the liability that the machine will be operated when unsupplied with stamps, or when it fails to operate properly and deposit or affix a stamp, 35 and so to produce an inaccurate record. My invention obviates this defect entirely, since no registration is made of the machine pulsations unless a unit, which the machine is designed to handle, is actually advanced to 40 affixing position, no matter how often the machine may be operated when unprovided with units, or when, by any possible chance, there is failure on the part of the mechanism to advance a unit, and this, coupled 45 with the positive and accurate counting of the units which are advanced and as they are advanced, is the primary object of my invention. This counting mechanism, in a word, is under the control of the units themselves, and not subject to other machine elements independent of said units.

Other objects and advantages will appear in the course of the following description.

A preferred form of embodiment of the invention, whereby I attain the objects and 55 secure the advantages of the same, is illustrated in the accompanying drawings, and I will proceed to describe the invention with reference to the latter, although it is to be understood that the form, construction, arrangement, etc., of the parts and members in various aspects are not material and may be modified without departure from the spirit of the invention.

In the embodiment of the invention as 65 herein illustrated I have represented the same in connection with or as applied to or forming part of a machine for affixing postage stamps to envelopes and other wrappers for mail matter, and I will describe it as 70 thus illustrated, without, however, limiting myself in any way to such application, since the subject matter of this application is wholly or in part adapted for other purposes and may be put to other uses, as before intimated.

The counting mechanism is intimately connected or associated with certain feeding and other elements, which in and by themselves form the subject matter of the herein-before-mentioned application, or of United States Letters Patent, No. 1,077,954, and it is necessary to include herein such elements, there being close combinations in some cases and need for their presence in order to obtain a clear understanding of function in other cases.

In the drawings, in which like numerals designate like parts throughout the several views, Figure 1 is a side elevation of a stamp 90 affixer in which is embodied the aforesaid form of my invention, the major portion of the front side plate being broken away and the several parts and members being normally or initially disposed; Fig. 2, an enlarged top plan of certain portions of the counter or counter-releasing mechanism and the feed mechanism which, if not a part of the former mechanism, is very closely allied therewith; Fig. 3, an enlarged bottom plan 100 of the hanger and parts of the mechanism supported thereby or mounted therein; Fig. 4, an enlarged detail, in partial section, showing the counter-operating arm and the releasing mechanism therefor; Fig. 5, a 105 front side elevation of the parts in Fig. 2,

the front sides of the tray and hanger being broken away at their bases, and, Fig. 6, a front side elevation of the same parts shown in the preceding view, with the hanger and tray in section, showing the operation of the lifter which is included in the counter mechanism.

Comprised in this machine, with a suitable supporting frame or case 1, is a plunger 2 which extends above and has its active or operative end inside of said case. The plunger, in practice, is provided at the base with stamp-pressing members, which are not herein shown, as they are not required for a full and clear understanding of the present invention. The counter-releasing portion of the counter mechanism is indirectly operated by the plunger 2, provided a stamp be advanced, excepting when the stamps are initially introduced into the feeding and counter mechanism, an independent and direct manual action on the part of the operator then being required, while the mechanism which does the actual counting is more directly operated by said plunger.

In my description of the counter mechanism and of the machine as a whole, including the operations of the same, it will be assumed that generally and for the sake of convenience, the terms front and back, or equivalent expressions, as applied to said mechanism and machine longitudinally, refer respectively to the left-hand and right-hand ends of such mechanism and machine, and that the same or equivalent terms or expressions, as applied to said mechanism and machine transversely, refer respectively to the sides of the same which are nearer the observer and to the opposite sides thereof.

Referring to Fig. 1, it will be observed that the case 1 is provided at the rear end with a door 3, which may be fastened with a lock and key, the latter appearing at 4. A partition 5 extends downward from the top of the case about midway between the ends thereof and curves rearwardly to form in said case a compartment or chamber 6 for a stamp roll 7. The rest of the interior of the case is open and contains practically all of the operating parts and members, such open space being designated by the numeral 8. The space or compartment 8 is not only in front of the partition 5, but also extends below it and communicates with the stamp-roll chamber 7 behind the bottom edge of said partition. A counter 9, of any usual and approved variety, is fastened against the inside of the front end of the case 1, and there is a slot or sight opening, indicated by dotted lines at 10, in such end, of sufficient size to enable the figures of said counter to be seen from outside of said case. The counter 9 has a shaft 11 for operating the counter mechanism proper, as is customary in devices of this kind, and said shaft pro-

trudes from one end of said counter. In the top of the case 1, forward of the partition 5, is an opening for the plunger 2, which extends through such opening and operates up and down therein. A vertical slot, indicated by dotted lines 12, is made in the front wall of the plunger opening to admit of the passage of a pin 13 set in the front of the plunger 2. A water tank or reservoir 14, having a wick 15 extending out of the top adjacent to the front end thereof, is located in that part of the compartment 8 which extends under the partition 5. The stamp roll 6 is mounted on a roller 16, which in turn is loosely mounted on a stud 17 carried by an arm 18 that is pivoted at 19 to the front side of the case 1. An unwound portion from the roll 6 appears at 20 in the first view. It may be noted here that the roll 6 consists of a perforated strip of stamps wound with the adhesive surface inside, as supplied by the Post Office Department.

Proceeding now to a further description of the counter mechanism, and having special reference to Fig. 4, it will be seen that the shaft 11, of the counter 9, is provided on its exposed terminal with an angular operating arm 21. This arm is rigidly secured on the shaft 11, and the major portion of the same is behind the vertical plane of said shaft. The arm 21 at its free end normally rides on a roll 22 which is mounted on a stud 23 that projects inwardly from the rear arm of a pair designated by the numeral 24. Said arm, when free, is forced onto the roll 22 by means of a spring 25 which encircles the shaft 11 and has one terminal bearing against the front end of the case 1 and the other terminal on the upper edge of the arm. A hook 26 is formed on the free end of the arm 21 above the part that is designed to ride on the roll 22. The parts 22, 23 and 24 are indicated by dot-and-dash lines in Fig. 4.

Mounted to rock on an inwardly-projecting fixed stud 27, set in the back side of the case 1, is a detent 28 for the arm 21. The detent 28 depends from the stud or pivot 27 and has a hook 29 at its base arranged to take position in the path of the hook 26 when the arm 21 is occupying an approximately horizontal position, there being, however, enough clearance between the two hooks to enable said detent to swing clear of said arm when occasion requires; and said detent is provided with a long tail-piece 30 that is offset toward the longitudinal center of the machine and sweeps downwardly to the right to have its free terminal inserted in a socket 31 at the forward end of a counter-releasing member 32, a loose slip connection being thus formed. A spring 33 has one end inserted in or otherwise fastened to the stud 27, is coiled on said stud, and has its opposite end carried over the top of the tail-

piece 30 at or adjacent to the junction of said tail-piece with the detent 28 and behind the vertical plane of said stud, and so normally retains said detent with its hook 29 in the 5 path of the hook 26, and the counter-releasing member or counter-releaser 32 in operative position, as will presently be more fully explained.

The mechanism, of which the counter-releaser 32 forms a part, includes much of the mechanism by means of which the stamp strip 20 is fed forward, the two mechanisms being very intimately and closely related and connected and having double functions 10 at several points, hence the description of one necessarily includes the description of the other. These mechanisms or this mechanism, whichever way the matter may be viewed, will next be considered in detail. A 15 hanger 34, in the form of an open-ended trough-like structure, is provided with two pairs of overhanging ears 35 and 36, by means of which said hanger is fastened to the front and back sides of the case 1 above 20 the reservoir 14. The ears 35 and 36 spring from the upper edges of the sides of the hanger 34 and extend outwardly and downwardly so as to leave spaces between them and said sides. In the bottom of the hanger 25 34 are a central slot 37 and two parallel flanking slots 38. Mounted crosswise of the hanger in the sides thereof are two rods or spindles 39 and 40, the latter being in advance of the former and having protruding 30 terminals which prevent said spindle 40 from getting out of place, owing to the nearness of the sides of the case 1, and also serve another purpose as will presently appear. Mounted loosely on the spindle 39 in the center 35 thereof is a back-stop finger 41 which has a sharp lower terminal that projects through and below the hanger slot 37. The finger 41 is pressed downwardly and rearwardly by means of a spring 42 coiled around 40 the spindle 39 and bearing at one end on the front edge of said finger and at the other end on the rear edge of a lifter 43. Loose on the spindle 39 in front of the finger 41 is a counter-releaser return arm 44. The 45 arm 44 extends to the left from the spindle 39 and has a forwardly-extending lug 45 at its front end. The arm 44 is borne downward by means of a spring 46 coiled around the spindle 39 and bearing at one end on the 50 upper edge of said arm and at the other end on the aforesaid rear edge of the lifter 43. The counter-releaser 32 is pivoted at 47 against the back side of the arm 44 in line with the finger 41. The counter-releaser 32 55 has the socket 31 at its front end, also a serrated base or foot part, as shown at 48, that is below the pivot 47 and extends normally through and below the slot 37, and a forwardly-extending lug 49 between said pivot 60 and said socket. The lifter 43 is a horizon-

tal member having upwardly-projecting end pieces which are loosely mounted on the spindle 39, and one of which, the front one, is extended above such spindle to form a handle 50. A spiral-spring 51, stronger than 70 the springs 42 and 46, is wound on the spindle 39 and arranged with one end bearing beneath the spindle 40 and the other end on the front edge of the lifter 43, with the result that said lifter is held normally by said 75 spring 51, in the position shown in Fig. 5, with the front edge of the bottom of said lifter against the floor of the hanger 34. The lifter 43 is so constructed and mounted that its rear edge clears the floor of the 80 hanger when said lifter is swung forward. Except when otherwise supported, the arm 44 rests, under the influence of the spring 46, on the pivotally-attached counter-releaser 32 and the latter rests on the bottom of a tray 85 52, as appears in Fig. 4. The arm 44 is beneath the lug 49 and the downward movement of the socket terminal of the counter-releaser 32 is limited by said lug and arm. A resetter for the counter-releaser 32, and which is 90 also a stamp-feed-operating member, comprising two arms 53 which are rigidly connected at their left-hand ends by means of a rod 53^a, is mounted on the spindle 40, the latter passing through such arms in advance 95 or to the left of their right-hand ends. The construction and arrangement of parts are such that the rod 53^a is in operative position relative to the wick or moistener 15. The aforesaid resetter is forced downward by 100 means of springs 54—54 coiled around the spindle 40 and bearing with opposite ends respectively on the upper edges of the arms 53 and beneath pins 55—55 that project inwardly from the sides of the hanger 34. 105 When released to the springs 54, the arms 53 retain the rod 53^a on the moistener 15. Pins 56—56 project laterally from the right-hand ends of the arms 53, and loosely mounted at their rear ends on these pins outside of 110 said arms are two generally arcuate jaws 57. The jaws 57 have inwardly directed lugs 58—58 on their front terminals, which lugs extend above the arms 53, and the bottom edges of said jaws are serrated, as shown 115 at 59. The serrated portions of the jaws 57 extend into and through the slots 38 and bear on the tray 52, except at such times as they are withdrawn from such position. The jaws 57 are forced downward and rearward by means of springs 60—60 coiled on the pins 56 and bearing with opposite ends respectively on the edges of said jaws, which are directly in front and below the horizontal plane of said pins, and beneath the coils 120 of the springs 54 on the spindle 40. The serrations or teeth 59 have their sharp edges directed to the left, while the serrations or teeth 48 have their sharp edges directed to the right, the reason for which will appear 125 130 135 140 145 150 155 160 165 170 175 180

directly. The lug 45 extends over the front arm 53 to enable the arm 44 to be raised by said arm 53.

The tray 52, like the hanger 34, is an open-ended trough, and it is adapted with its sides to fit the sides of said hanger inside of the ears 35 and 36, and to be so attached to said hanger that there is a space left between the floors of the two members, as can be plainly seen at 61, in Figs. 4, 5 and 6. The tray 52 is supported from the hanger 34 by means of the protruding terminals of the spindle 40, which are received in notches (not shown) in the front edges of the sides of said tray, and a hook 62 formed on the upper edge of the back side of said tray and arranged to fit over the top of the ear 36 that springs from the back side of said hanger. A latch 63, pivoted at 64 to the back side of the tray 52, is provided to engage the aforesaid ear. The latch 63 is normally held in locking engagement with the ear just referred to by means of a spring 65 coiled on the pivot 64 and bearing with one terminal against the underside of the latch handle and with the other terminal on a pin 66 which is set in the tray behind said pivot. Thus supported the tray is removable from the hanger.

30 The front end of the floor of the tray 52 is serrated and bowed upwardly slightly to afford means for catching and holding the stamps at the time they are torn apart, such serration appearing at 67.

35 The operation of the combined counter-releasing and stamp-feeding mechanism is thus explained. The lifter 43 is swung forward on the spindle 39, through the medium of the handle 50, to raise the sharp end of the finger 41 and the serrated portions of the counter-releaser 32 and the jaws 57 upward in the slots 37 and 38 and thus clear the passage 61 for the introduction of the stamp strip 20. The elevation of the parts 40 just mentioned is effected by reason of the fact that the front edge of the lifter 43, when swung forward, encounters the adjacent edges of the finger 41 and the jaws 57, which swing forward and upward on the spindle 39 and the pivots 56, respectively, and against the resiliency of the springs 42 and 60, respectively, and by reason of the further fact that the front edge of said finger encounters the adjacent or contiguous edge of the counter-releaser 32, which rocks on the pivot 64, against the resiliency of the spring 33, into the desired position. The parts, including those the operation of which has not yet been explained, are now 50 disposed as shown in Fig. 6. Upon the release of the handle 50, the displaced parts are immediately returned to their normal positions by their respective springs, the spring 57 being of sufficient strength to 65 overcome the resistance offered by the

springs 42 and 46. When the counter-releaser 32 is rocked into the position as represented in Fig. 6, the tail-piece 30 and the detent 28 are actuated with it, rocking on the stud 27, so that the hook 29 is taken out 70 of the path of the hook 26, but at this time such action has no significance, being merely incidental to the operation of the connected parts. The function of the finger 41 is to prevent backward movement on the part of 75 the stamp strip 20 in the tray 52.

The jaws 57 engage with their serrated edges 59 the stamps in the passage 61 and advance them when the arms 53 are so rocked on the spindle 40 as to elevate the 80 forward ends and depress the rear ends of said jaws, as when the front ends of said arms are raised, because a rolling or sliding motion forward on the tray 52 or on a stamp or stamps therein is then imparted 85 to such edges. The jaws 57 slide backward, upon the rocking of the arms 53 in the opposite direction or back to normal position, or the serrated edges 59 slide backward at this time and take position in 90 readiness to further advance the stamps at the subsequent upward tilt of the front terminals of said arms, and it is then that the stop finger 41 becomes effective, since said jaws necessarily drag on the stamps 95 when returning to active position. The lugs 58 prevent the jaws 57 from dropping too far when the tray 52 is removed.

The parts are so timed in their respective operations that the counter-releasing mechanism is operated once for each stamp that passes under the counter-releaser 32, or, in other words, each stamp advanced to be affixed is counted or registered. No registration is made of any movement of the machine or its parts without the actual advancement of a stamp to affixing position. To this end, that is, to prevent registration of the operations of the machine when no stamp is actually delivered, the detent 28 is 100 provided, which detent must be moved away from the arm 21 in order that the act of registration may be performed, and this latter can be done only when a stamp passes forward under the counter-releaser 32 and at 105 no other time. The forward passage of a stamp in the tray 52 under the serrated part 48 of the counter-releaser 32 actuates such part forward and so rocks said counter-releaser on the pivot 47 and throws upward 110 the socket 31, the latter carries with it the tail-piece 30 and thus swings the detent 28, on the stud 27 and against the resiliency of the spring 33, rearwardly, and the hook 29 is withdrawn from the path of the hook 26 115 and no longer acts in the capacity of an obstacle or obstruction to the operation of the counter 9. The counter-releaser 32 is now 120 out of operative position and must be reset, in fact the counter-releasing mechanism as 125 130

a whole, including the detent 28, must be reset. The resetting of the aforesaid mechanism is effected in this manner: After the counter-releaser 32 acts to release the 5 counter the arms 53 are elevated at their forward ends, and in changing position the lug 45 is encountered and the arm 44 is rocked upward on the spindle 39 against the resiliency of the spring 46, with the result 10 that the pivot 47 is raised high enough for the part 48 of the counter-releaser to clear the tray bottom and so to enable said counter-releaser to be returned to operative position by the spring 33 acting through 15 the medium of the tail-piece 30. The movement in the opposite direction of the arms 53 leaves the lug 45 behind and the counter-releaser bears once more on the tray bottom or on an interposed stamp, the spring 46, 20 acting through the arm 44 and the pivot 47, holding down said counter-releaser. The spring 33 returns the detent 28 to operative position with its hook 29 under the hook 26, and also causes the counter-releaser 32 to be 25 swung so that its base is in the backward operative position, as noted, and retains such base in such position until the next stamp is drawn beneath it. The counter-releasing mechanism is most clearly shown 30 in its set condition in Figs. 4 and 5.

The counting of the stamps is directly brought about by the stamp-transfer mechanism of the machine, which includes the arms 24, and this mechanism will next be 35 briefly described. Each arm 24 is pivotally mounted at its upper front and on a stud 68, and is connected at the opposite end with the companion arm by a transverse plate 69 which constitutes the lower stamp-transfer 40 or gripping jaw. The studs 68, for the arms 24, are set in the inside faces of the front and back sides of the case 1, and, although most of the front side of said case 45 is broken away in the first view, the stud which is set therein is left and shown in section for the sake of clearness in illustrating and describing the mechanism of which said stud forms a part. Rising from the free end of each arm 24 is a cam projection 70. 50 Associated with the jaw 69 is an upper stamp-transfer or gripping jaw 71 having two arms (one of which is shown at 72 in Fig. 1) rigidly connected with the ends thereof. The front end of each arm 72, as 55 summing that the parts are in their elevated, initial or starting positions, as will be assumed for the purpose of the present description, is pivoted at 73 to one of the arms 24 inside of the same. A horizontal cross-head 74 is let into the back side of and secured to the plunger 2. Having its upper end pivotally attached at 75 to each side of the cross-head 74 is one of a pair of links 76. The lower end of each link 76 is pivoted at 60 77 to one of the arms 72 on the inside and

above the jaw 71, and such link is provided on its opposite side above the adjacent pivot 77 with a roll 78. These rolls are designed to contact with the cam-projections 70 at certain times. A roll 79 is mounted on each 70 pivot 75, outside of the adjacent link 76, and located by the cross-head 74 and such pivot within a slot 80, in each side of the case 1, and travels up and down in such slot when the plunger 2 is reciprocated, thus guiding 75 and steadyng said plunger and the parts connected therewith and operated thereby and preventing the plunger from turning on its axis. The jaws 69 and 71 are so constructed that their contiguous surfaces can 80 be brought tightly together. A spring 81 is coiled around a rod 82, which latter is mounted in the sides of the case 1, and said spring has a looped middle portion that extends downwardly and bears against the 85 front end of said case, and has its free ends extended rearwardly and arranged to bear each beneath each pivot 73. The purpose of the spring 81 is to swing the arms 24 upward on their pivots 68 until they contact 90 with stops which project inwardly from the sides of the case 1, (one of such stops appearing in Figs. 1 and 4), and elevate the plunger 2 together with all attached parts, and to retain such arms, plunger and parts 95 thus elevated in such condition. When the arms 24 are in contact with the stops 83, the back edge of the jaw 69 is in approximately the same horizontal plane with the serrated edge 67 of the tray 52. 100

A lifter arm 84 is loosely mounted at its front end on the front stud 68, inside of the front arm 24, and bears with its opposite terminal against the adjacent roll 78 from below, being held in contact with said roll 105 by means of a spring 85. The spring 85 is capable of lifting the links 76 and attached parts still higher, through the medium of the arm 84. As the result of the upward movement thus imparted to the links 110 76 the plunger 2 is raised into its highest position, and the upper gripping jaw is caused to separate from the lower gripping jaw. The gripping jaws are thus left wide open. Not only are the springs 81 and 85 115 able to do the work already mentioned, but they have sufficient additional strength to actuate the counter-releasing and stamp-feed-operating mechanism and the counter-operating arm, as will appear from the explanation below. 120

The upper jaw 71 extends under the front end of the stamp-feed-operating member consisting of the arms 53 and the rod 53^a and raises such end, said arms rocking on the 125 spindle 40 against the resiliency of the springs 54, when said jaw moves upward under the influence of the springs 84 and 85.

If the detent 28 is out of the way when the arms 24 swing downward, the arm 21 follows 130

down on the roll 22, under the influence of the spring 25, and operates the counter-mechanism to register the stamp carried down by the gripping jaws; and when said arms 24 swing upward, under the influence of the spring 81, said arm 21 is rocked upward, against the resiliency of said spring 25, into position to operate said counter-mechanism at the next downward sweep of 10 said arms 24.

The plunger 2 is forced downward by hand, and in its descent said plunger first closes the upper jaw 71 on to the lower jaw 69 through the medium of the cross-head 15 74 and the links 76, then, through the same medium and by reason of the contact of said upper jaw with said lower jaw, forces said jaws downward and forward together, and, finally, through the medium of the rolls 20 78 which advance on to the cam-projections 70 forces the arm 24 still farther forward and separates said jaw 69 from said jaw 71. Meanwhile the arms 53 have with their front ends and the rod 53^a 25 and under the influence of the springs 54 followed down on the jaw 71 until said jaw passes away and leaves said rod resting on the moistener 15, and the counter-operating arm 21 has followed down on the roll 22, 30 unless held up by the detent 28.

Upon the release of the plunger 2, the spring 81 immediately acts to raise said plunger with the directly and indirectly connected or associated parts, the first result of this being that the rolls 78 pass away from the cam-projections 70 so that the gripping jaws can close. In swinging rearwardly and upwardly the jaw 71 rises beneath the rod 53^a and elevates it with the attached 35 parts of the arms 53, the arm 84 completing this part of the operation; and at the same time the roll 22 returns the arm 21 to its former position, provided said last mentioned arm followed down on said roll.

As hereinbefore intimated, a presser for the stamp, after it has been deposited on the envelop or other object, is provided at the base of the plunger 2, but there appearing to be no need of a disclosure of the same 45 here, such presser is omitted from both the drawings and specification.

A stop or check device is provided for the plunger 2, for the purpose of preventing said plunger, after being started in either direction, from being impelled in a contrary direction until the full stroke is made. Such device comprises an oscillatory lock-plate or clutch 86. This clutch has an opening for the plunger, is arranged transversely in the 55 case 1, and has trunnions journaled in elongated openings in the sides of said case. The trunnions are at the front ends of the lateral edges of the clutch 86, and one of them is shown at 87, in Fig. 1, while at 88, 60 in Figs. 1 and 4, appears one of the elongated openings for the trunnions. The back edge of the clutch 86 is beveled to form a double bearing 89. A flat spring 90 is secured at the base to the front side of the partition 5, and has a forwardly-extending 70 angular head 91 at the top to engage the bearing 89. The pin 18 is above and the cross-head 74 below the clutch 86; and the arrangement of parts is such that said pin encounters said clutch from above, just before the plunger arrives at the end of its down stroke, turns said clutch downward, and forces the bearing 89 below the head 91 of the spring 90, or below the apex of said head, by the time said plunger completes 75 said stroke; and said cross-head encounters said clutch from below, just before said plunger arrives at the end of its up stroke, turns said clutch upward, and forces said bearing above said apex, by the time said plunger completes said last-mentioned stroke.

Beyond the following supplementary statements, nothing more need be added to what has gone before in regard to the operation 90 of the machine as a whole or of that part thereof which comprises the present invention.

Initially the loose end of the stamp strip 20 is led down from the front of the stamp roll 6, behind the bottom edge of the partition 5, to the floor of the tray 52, and pushed through the passage 61 until a narrow portion of such end projects onto the working edge of the lower jaw 69, the handle 50 having meanwhile been pressed down to clear said passage. As soon as the stamp strip is thus placed, the handle 50 is released and the finger 41, counter-releaser 32 and jaws 57 permitted to move down on to said strip, the engagement being with the ungummed surface of the strip, which is uppermost in the tray.

When the plunger 2 descends, the upper jaw 71 is closed onto the lower jaw 69 and the advance edge of the first stamp in the strip is tightly gripped between said jaws, and the rod 53^a is lowered onto the moistener 15 and onto said stamp which is between said moistener and said rod. As the jaws 69 and 71 continue to descend, impelled by the plunger, the stamp in the grip of said jaws is drawn by the latter over the moistener and downward, and the strip 20 moves with said stamp until the perforated portion between the first and second stamps reaches the serrated edge 67, when said first stamp is torn from the rest of the strip. As the stamp is thus drawn forward, it actuates the counter-releaser 32, which is resting on said stamp, to withdraw the detent 28 from the path of the arm 21, and the counter is operated to register the stamp. Another action that occurs, as one of the results of the descent of the plunger, is the backward 110

setting of the stamp-feed jaws 57 to locate them in position further to advance the strip 20, the finger 41 preventing said strip from being carried backward with said jaws 5 at this time.

The plunger 2 in ascending not only causes or permits the counter-releaser 32 to be reset and the detent 28 to be returned to operative position relative to the arm 21, 10 which latter has been rocked up into initial or operative position by the agency that is doing the work at this time, but permits the jaws 57 to be rolled or pushed forward and in turn to push the second stamp, which is 15 now the leading stamp, out over the jaw 69 waiting to receive it.

What I claim as my invention, and desire to secure by Letters Patent, is—

1. Mechanism, of the class described, comprising a counter, operating means for such counter, means to render said counter-operating means inactive, and means operated by an advancing unit to release said counter-operating means.

2. Mechanism, of the class described, comprising a counter, operating means for such counter, unit-actuating means, means to render said counter-operating means inactive, and means, operated by an object advanced 30 by said unit-actuating means, to release said counter-operating means.

3. Mechanism, of the class described, comprising feeding mechanism, transfer mechanism, a counter, locking and releasing 35 means for such counter, and a plunger arranged and adapted to operate both of said mechanisms and said counter when unlocked and to reset said locking and releasing means.

4. Mechanism, of the class described, comprising means to detach a unit from a flexible strip, coacting means to count the same, counter-controlling means, operated by the strip when advanced and means to advance 45 the strip to present another unit for detachment and to reset said counter-controlling means, said advancing means being controlled by said detaching means.

5. Mechanism, of the class described, comprising a supporting frame provided with a counter, a plunger mounted to reciprocate in said frame, cooperating spring-pressed gripping jaws mounted to oscillate in said frame and operatively connected with said 55 plunger, counter-operating means dependent for action on the action of said jaws, and flexible strip- or unit-feeding mechanism and counter-releasing mechanism within said frame, said feeding mechanism being operated by the gripping-jaw mechanism, and said counter-releasing mechanism being operated by a strip or unit in the grasp of the jaws, and reset by said gripping-jaw mechanism.

6. The combination, in mechanism of the

class described, with members arranged to form a passageway for a flexible strip of units, a counter, and a member adapted when free to actuate said counter, of a detent member adapted normally to prevent 70 said counter-actuating member from operating, and means extending into said passageway, onto the upper surface of such strip or a unit thereof, to be frictionally engaged and operated by such strip or unit, to withdraw said detent member from detaining position relative to said counter-actuating member, when the strip or unit moves forward.

7. In mechanism, of the class described, 80 flexible unit strip-feeding and counter-releasing mechanism comprising, with members arranged to form a passageway for the strip, surface engaging means extending into such passageway for such strip to advance 85 the latter intermittently, and surface-contacting means extending into such passageway to be engaged and operated by such strip or a unit thereof each time it advances.

8. In mechanism, of the class described, 90 counter-releasing mechanism, for flexible units from a strip, comprising, with members arranged to form a passageway for the strip, means extending into said passageway to be engaged and operated by such strip or 95 a unit thereof when it moves forward, and oscillatory means to reset automatically such first-mentioned means after being so operated.

9. The combination, in mechanism of the 100 class described, with an oscillatory strip- or unit-contacting counter-releasing member, of manually-operated means to move said member out of operative position.

10. The combination, in mechanism of the 105 class described, with an oscillatory strip or unit-contacting lifter, of a manually-operated pivotally-mounted counter-releaser arranged in the path of said lifter and adapted to be actuated out of operative position 110 thereby.

11. The combination, in mechanism of the 115 class described, with passageway-forming members, of a spring-pressed rocking member, a rocking arm having a part which extends into the path of said rocking member, a counter-releaser pivotally connected with said rocking arm and operating in the passageway formed by said first-mentioned members, said counter-releaser being adapted to bear on the bottom passageway-forming member and to support said arm with the aforesaid part thereof out of contact with said rocking member, and means to operate said rocking member against the 120 force of its spring, and, through the medium of said arm and said part, to elevate said arm and reset said counter-releaser.

12. The combination, in mechanism of the 125 class described, with a counter-operating

arm, of a detent arranged normally to prevent said arm from operating, passageway-forming members, and an oscillatory member operatively connected with said detent and having a part to extend into the passageway formed by said first-mentioned members.

13. The combination, in mechanism of the class described, with a counter-operating arm, of a detent arranged normally to prevent said arm from operating, passageway-forming members, a spring-pressed rocking member, a rocking arm having a part which extends into the path of said rocking member, an oscillatory counter-releaser pivotally attached to said rocking arm and operatively connected with said detent, said counter-releaser having a part which extends into the passageway formed by said first-mentioned members, and being adapted to bear on the bottom passageway-forming member and to support said arm with the aforesaid part thereof out of contact with said rocking member, and means to operate said rocking member against the force of its spring, and, through the medium of said arm and said part, to elevate said arm and reset said counter-releaser.

14. The combination, in mechanism of the class described, with a supporting frame, a

reciprocable plunger mounted to operate in said frame, and a gripping jaw having arms pivotally attached to said frame and spring-pressed in one direction, said arms being operatively connected with said plunger, of counter mechanism within said frame and provided with an operating member in the path of one of said arms, said member being adapted to move with said arms to operate said counter mechanism, when said arms are caused to make their active stroke, and to be returned to initial position by the operating arm therefor, when said arms return to initial position.

15. Mechanism, of the class described, comprising, with advancing members for flexible units, a counter, counter-operating means co-operating with said advancing members, and means to prevent such counter from registering except when a unit is actually advanced by said members, said last-mentioned means being dependent for its counter-releasing action upon direct contact with a flexible unit or units advanced by said member.
